UNITED STATES PATENT OFFICE.

STATES LEE LEBBY, OF CORNING, NEW YORK, ASSIGNOR TO CORNING GLASS WORKS,
OF CORNING, NEW YORK, A CORPORATION OF NEW YORK.

SIGNAL LAMP.

Application filed August 30, 1923. Serial No. 660,211.

This invention is an improvement in signal lamps or projectors and more particularly to focusing means therefor.

The invention aims to provide a focusing means of a simple and economical nature which may be readily manipulated without requiring access to the interior of the lamp. The invention further aims to provide a construction which will afford extreme accuracy 10 of adjustment, and by which accidental movement of the several parts of the lamp due to various causes will be prevented.

With these and other objects in view the invention includes the novel features of construction and arrangement and combination of parts, hereinafter described and particularly defined by the appended claims.

An embodiment of my invention is illustrated in the accompanying drawings in 20 which:—

Fig. 1 is a vertical longitudinal section taken through a signal lamp incorporating the invention.

Fig. 2 is a vertical transverse section taken 25 on the line 2—2, of Fig. 1;

Fig. 3 is a rear view, with the rear cover removed;

Fig. 4 is a detail view of a portion of the light-supporting means;

Fig. 5 is a perspective view of the bracket and guide; and

Fig. 6 is a sectional view of the bracket and guide taken on the line 6—6 of Fig. 5.

My invention is capable of embodiment in 35 practically any known type of light projector employing an incandescent light source, but for convenience I have illustrated it in connection with a signal lamp, such as is mounted on semaphore poles of railway signal apparatus.

In the drawings the numeral 1 designates 45 the lamp casing, having a reflector 2 mounted in its rear by means of a screw connection 3, and its open front provided with a cover-glass 4. The cover-glass is retained in position by means of a front plate 5 fastened to the front of the casing by screws 6. Interposed between the front face of the casing and the plate 5 is an annular disk 7 having 50 an opening 8 therein of less diameter than the cover glass. This disk, which is held in position by tapered pins 9 driven through the front of the plate as shown, is in the nature of a focusing target, and substantially the whole of the beam of projected 55

light passes through the opening 8 thereof, as is described in my U. S. Patent, No. 1,518,155.

Formed integral with the lower portion of the plate 5 and extending rearwardly therefrom is a horizontal arm 10 having its under face formed into a perforated semi-spherical socket 11. An inverted semi-spherical cup 12 having an opening 13 formed centrally therein, rests upon a bracket 14 of a signal pole, 60 and has its upper and outer curved face positioned in the socket 11 of the arm 10. The arm 10 is attached to the bracket 14 by a bolt 15 which is passed through the perforated socket 11, the opening 13 of the cup 12, 65 and an opening 36 formed in the bracket 14, as shown in Fig. 1. In this manner, the construction provides for universal movement of the casing with respect to a fixed support, and as will be readily understood, the lamp 70 can be accurately adjusted to the desired position, and then positively retained in such position.

The lamp bulb, which is indicated by the numeral 16, is supported by a socket 17 75 clamped to the upper end of a standard 18. The standard is formed by doubling a suitable length of stiff sheet metal upon itself to provide a flat, thin central portion, and upper and lower eyes 20 and 21, respectively, 80 the upper eye 20 receiving the socket 17, while the lower eye 21 is fixed on a horizontally disposed rod 22 near one end thereof. This end of the rod passes with a slight clearance through an opening 22' in the bracket 24. 85

The standard is slidably mounted in a guide formed by doubling the upper portion of the sheet metal from which the bracket is made, upon itself, until the walls 19 are brought into tapering relation toward their free edges, a channel 23 being thus formed between the walls. The rear portion of the channel is occupied by the feed wires for the bulb. The edges of the walls 19 have a sliding fit against the standard. Thus the standard may slide within its own plane in the guide, and may be turned therein upon the edges of the walls 19, as fulcrums. 95

The outer end of the rod 22, which is threaded, as shown, projects through a large opening 25 formed in the rear of the casing, and then passes through a smaller opening 26 in an arcuately shaped plate 27. A thumbscrew 28, having a flange 29, is threaded on 105 the outer end of the rod, and is so disposed 110

with respect to the plate, that when the parts are assembled as shown, the upper portion of the flange of the nut will be on the inside of the plate, while the lower portion of the flange will be on the outside of the plate, and in this manner longitudinal movement of the nut with respect to the plate is prevented, when the nut is turned on the rod, while the rod will be moved longitudinally, as will be understood.

For the purpose of retaining the parts in proper position, and taking up lost motion, a coiled spring 30, having one of its ends connected to the rod near the threaded end there-
15 of and its other end connected to the bracket 24, is provided. When the parts of the lamp bulb supporting structure are being adjusted, the spring will serve as means for resiliently retaining the parts in adjusted position be-
20 fore being locked, and also for taking up any lost motion of the parts, and further serves to bind the nut 28 in adjusted position, there-
by preventing accidental movement of the nut.

25 When the light bulb is being shifted so as to bring it to proper focus, it is necessary to move its supports with respect to the axis of the casing, so as to impart movement of the light source in a plane perpendicular to the axis of the lamp, thus centering the light source on the axis, so for this purpose, the plate 27 is provided with a slot 31 that is cut into its upper end, as shown by Fig. 3, which allows vertical movement of the plate. A
30 stud 32^a, which is threaded into the casing above the opening 25 has its shank passed through the slot 31, and carries a nut 32 thereon bearing against the plate 27. When the nut is loosened the plate can be shifted in any direction to properly center the light source. Thus vertical movement of the rear or outer end of the rod may be had by moving the plate vertically, this being allowed by the slot 31, and transverse movement of
40 the rear end of the rod may be had by moving the plate about the stud, as a pivot.

45 To adjust the light source in accurate focal relation with the reflector, the nut 28 is turned in a proper direction to obtain the proper focal distance, i. e., such distance that a beam of such spread as to fill the opening 8 in the disk 7, is produced, by shifting the light source back or forth with respect to the reflector. The light source is then accurately centered by loosening the nut 32 on the stud 32^a and adjusting the plate 27, by swinging the rod 22 in the opening 22' as a pivot to move the light source transversely with respect to the axis of the projector, until it is
50 on the axis, at which point the beam will be accurately directed through the opening 8. The parts are then locked in position by turning the nut 32 down on the stud 32^a.

55 As heretofore stated, the plate 27 is arcuately shaped. This arcuately shaped plate

fits against a correspondingly arcuately or spherically shaped face of the casing. The center of curvature of the plate 27, and the spherical surface of the casing against which it moves is at such a point below the axis of 70 the reflector, and the radius or curvature of the plate 27 is such, that when the centering adjustment is being made, i. e., the adjustment which brings the light source to the position for directing the beam through the opening 8 in the disk 7, the light source will move in such a curve that the spread of the projected beam will not be disturbed, although its direction will be varied as the light source is moved. Hence, in adjusting the light 80 source, the longitudinal adjustment which varies the spread of the beam is made by turning the nut 28 in the proper direction, and then the transverse or centering adjustment is made by moving the plate 27, but the centering adjustment which shifts the direction of the beam, does not disturb the first adjustment which controls the spread of the beam, by reason of the curved path which the light 85 source traverses in making the centering adjustment.

90 For the purpose of preventing accidental or unwarranted handling of the adjusting means, the lower portion of the rear of the casing is enclosed by a cover 33 which may be locked in position in any desired manner, as by a pad-lock, as indicated by the numeral 34.

Having thus described the invention, what is claimed is:—

1. The combination with a projector casing 100 and its light source, of means for supporting and focusing the light source comprising a standard carrying said source at its upper end, a rod on which the standard is carried, said rod having its outer end projecting through the casing, a guide bracket for said standard carried by said casing in which the rod is movably mounted, and means carried by the casing for shifting the outer end of the rod in all directions.

110 2. A focusing mechanism for projecting lamps, comprising a rod arranged longitudinally of the lamp, a standard carried by and substantially at right angles to the rod, said standard being mounted in front of the mirror, a socket for the light source carried by the standard substantially in the optical axis of the lamp, a guide for the standard in which the rod is slidably and pivotally supported, and means for universally adjusting the rod 115 with respect to the guide.

120 3. The combination with a light projecting mirror of a socket for a light source arranged substantially in the optical axis of the mirror, a standard substantially at right angles to the socket and on which the latter is carried, a rod substantially at right angles to the standard and on which the latter is carried, such rod extending to one side of the socket 125 and mirror, means supporting the end of the 130

rod forward of the mirror for sliding and universal pivotal movement, a plate in which the rod is carried adjacent its rear end, means cooperating with the plate for imparting 5 longitudinal movement to the rod, such plate being movable substantially in its own plane to impart upward, downward, and sidewise movement to the rod.

4. The combination with a light projector 10 of a socket for the light source arranged substantially in the optical axis of the projector, a standard substantially at right angles to and supporting the socket, a rod off-set from and substantially parallel to the socket and 15 on which the standard is mounted, means supporting one end of the rod for sliding and universal pivotal movement but preventing rotary movement of such rod, and means by

which the other end of the rod can be adjusted in any direction. 20

5. In a projector, the combination of a reflector, a socket for the light source arranged substantially in the optical axis of the reflector, a single rod offset from and substantially parallel to the optical axis of the reflector, a standard supported by the rod and carrying the socket, means supporting the end of the rod adjacent the standard for sliding and universal pivotal movement and preventing rotary movement of such rod, and means 25 supporting the opposite end of the rod for universal movement. 30

In testimony whereof I hereunto affix my signature.
